UNITED STATES PATENT OFFICE.

PAUL T. CAMPBELL, OF GREENWICH, CONNECTICUT.

SELF-STARTER FOR AUTOMOBILES.

1,101,833.

Specification of Letters Patent. Patented June 30, 1914.

Application filed April 3, 1913. Serial No. 758,537.

To all whom it may concern:

Be it known that I, PAUL T. CAMPBELL, a citizen of the United States, residing in the city of Greenwich, county of Fairfield, State 5 of Connecticut, have invented certain new and useful Improvements in Self-Starters for Automobiles; and I do declare the following to be a full, clear, and exact description of the invention, such as will enable 10 others skilled in the art to which it appertains to make and use the same.

This invention relates to certain new and useful improvements in self starters for automobiles, and the object thereof is to provide novel and improved means for automatically firing the charge when a sufficient quantity of gasoline has been pumped into the spark plug or plugs, and a further object of the invention is to provide improved 20 means incorporated in a spark plug for cleansing the terminals thereof.

In the drawings: Figure 1 is a fragmentary side elevation, parts being in section, of the front portion of an automobile, showing 25 the present invention applied thereto; Fig. 2 is an enlarged detail vertical sectional view of the atomizer; and Fig. 3 is an enlarged view of one of the spark plugs, which latter is shown partly broken away and in section.

30 In proceeding in accordance with the present invention, an air pump 1 is secured in position adjacent to the dash-board of an automobile, and has the rod 2 of its piston extending through the dash-board. The rod 35 2 is pivoted at 3 intermediate the ends of a vertically disposed hand-operated lever 4, the latter being pivoted at 5 to the floor structure of the automobile. A bracket 6 or any other suitable supporting structure is at- 40 tached to the dash-board D and bears a vertically disposed member 7 that is spaced from the dash-board, and has a contact 8 at its upper end. A coil-spring 9 is interposed between the member 7 and the lever 4 for a 45 purpose shortly to be described. A gas tank T has a pipe connection 10 with an atomizer body 11 in order to feed gasoline to the latter, a check-ball valve 12 being mounted in the pipe connection to prevent back flow 50 of gasoline into the tank. Projected through the upper end of the body 11 is a pipe 13 which connects by means of a pipe 14 to the air pump 1, a check-ball valve 15' being interposed in said pipe 14 to prevent 55 return of the air into the pump. The pipe 13 has a series of pipes 15' connected there-

to, the latter leading to the respective spark plugs 16. A tube 17 has one end extending in the pipe 13 and its other end extending down into the body of the atomizer as is usual in the latter. Each spark plug 16 has a hollow body portion or chamber closed at its lower end at 17' and formed with a tubular portion 18 which affords the inlet and outlet of said chamber, which tubular portion preferably extends inwardly within said chamber, the bore of said tubular portion being preferably of conical form, the wall of such bore forming one of the terminals of the spark plug, the other terminal 19 being 70 a bare elongated wire which extends down into said bore so as to be suitably spaced from the wall of the latter. The pipes 15' have curved free ends 20 which extend through the sides of the bodies of the spark 75 plugs, in order to discharge the combustible mixture downwardly in the spark plugs. A battery coil and timer 21 is connected to the dash-board.

In operation the lever 4 is oscillated to 80 pump air through the pipe 14 and into the pipe 13, atomizing the gasoline in the body 11 and causing the atomized fluid to pass through the pipes 15' into the spark plug bodies. When sufficient atomized fluid has 85 been pumped into the spark plug bodies, a portion of same will be liquefied and will collect in the bottom of the spark plug as shown in Fig. 3, at which time the lever 4 in its oscillatory movements in which it en- 90 gages contact 8 will thereby close the circuit through the spark plug terminals, caus- 95 ing a spark which will ignite the gases in the chamber, the liquid fuel which collects in the bottom of the spark plug being ignited by the ignition of the gases. The contact 8 and the lever 4 are arranged in any suitable manner in electrical connection with the ignition system, for instance with one of the low tension terminals of such ignition 100 system.

The bore of the tubular portion may be either straight or conical, so long as the end of the terminal 19 is properly spaced from the wall of such bore, but I prefer the conical form of bore since it provides a wedge-shaped wall, so to speak, that surrounds the said terminal 19 and when the priming charge is ignited, as above described, the same will rush past the terminal 19 in es- 105 caping from the plug body and will be forced by the wedge-shaped walls to move 110

inwardly against the terminal 19 to forcibly engage the same to thereby wipe and clean the latter from the substances which commonly gather on said terminal. On the compression strokes of the engines, the charge will, in part, be forced to enter the plug bodies through the bores of the extensions 18 and since the lower ends of said bores are very small and the walls formed thereby closely surround the terminal, it will be seen that same will be further cleaned by the compressed charge, which must of necessity pass through the small end of the bore of extension 18 and due to the small size of said bore will cause the charge to rush past the terminal with great force. It is therefore of paramount importance that the walls formed by the bore of the extension shall be disposed in very close proximity to the terminal. Further by making the extensions long, the cleansing effect is enhanced, since the exploded charge is forced into intimate contact with the terminal throughout a greater portion of the length of the latter. An additional advantage of the conical bore, is, that should the sparking distance between the terminals be too little, this may be remedied by shortening the terminal 19 so that its end may be higher up within the conical bore and therefore separated by a greater space from the wall of the latter, and this shortening of the terminal may be effected in any suitable manner, either by making its normal length less or by adjusting the same by any ordinary means provided for the purpose of elevating or lowering the terminal. I prefer to extend the tubular portion within the hollow chamber since a convenient receptacle is thereby formed at the bottom of such chamber for any liquefied gas, but I do not wish to be limited in this respect since such tubular portion may project downwardly from the bottom of such chamber. As soon as the lever 8 is released by the operator, the spring 9 will return same to normal neutral position, depicted in Fig. 1 of the drawings.

What is claimed is:

1. In a self starter for automobiles, a spark plug having means therein to collect liquefied gasolene from the charge, means to atomize the gasolene and to force same into the plug, means to operate the atomizing means, a contact having electrical connection

with one of the low tension terminals of the ignition system, and an electrical connection between said operating means of the atomizing means, and the plug.

2. In combination with a spark plug having means therein to collect liquefied gasolene from the charge, manually operated means to force the charge into the plug, and a normally open electric circuit having a contact for engagement with the charge forcing means to close the circuit upon operating of the last named means said plug having contact with one of the low tension terminals of the ignition system.

3. In a self starter for automobiles, a spark plug having means therein to collect liquefied gasolene from the charge, atomizing means connected to the plug, an air pump connected to the atomizing means, a pivoted manually operated lever in electrical connection with one of the lower tension terminals of the ignition system, for operating the pump and a contact for engagement with the lever in electrical connection with the other low tension terminal of the ignition system.

4. In a self starter for automobiles, a spark plug having means therein to collect liquefied gasolene from the charge, atomizing means connected to the plug, an air pump connected to the atomizing means, a pivoted manually operated lever for operating the pump, a contact for engagement with the lever, said contact and lever being in electrical connection with the ignition system and means for normally maintaining the lever out of engagement with said contact.

5. A spark plug having at its lower end a hollow chamber having a perforated bottom, the latter formed with an elongated flared tubular portion which affords the inlet and outlet to said chamber, the inner wall of said tubular portion forming one terminal, and an elongated wire extending through said hollow chamber within said bore and properly spaced therefrom at the sparking point and constituting the other terminal.

In testimony whereof I affix my signature in presence of two witnesses.

PAUL T. CAMPBELL.
